[57] CLAIM

The ornamental design for a lift handle for a toilet seat cover or the like, as shown and described.

DESCRIPTION

FIG. 1 is a rear elevational view of a lift handle for a toilet seat cover or the like showing my new design;
FIG. 2 is a left end elevational view thereof;
FIG. 3 is a top plan view thereof, the bottom being a mirror image of the top;
FIG. 4 is a right end elevational view thereof;
FIG. 5 is a front elevational view thereof; and,
FIG. 6 is a perspective view taken from the top, front and left end thereof.

FIG. 1

FIG. 2

FIG. 3

FIG. 4

FIG. 5

FIG. 6
